CLAIM

The ornamental design for a grill, as shown and described.

DESCRIPTION

FIG. 1 is a perspective view of a grill according to the present invention.

FIG. 2 is a front view of the grill of FIG. 1.

FIG. 3 is a side view of the grill of FIG. 1 shown in an open position, the opposite side view being a mirror image thereof.

FIG. 4 is a side view of the grill of FIG. 1 shown in a closed position, the opposite side view being a mirror image thereof.

FIG. 5 is a rear view of the grill of FIG. 1; and,

FIG. 6 is a top view of the grill of FIG. 1.

The claimed grill design can be used on grills for making, among other things, Panini sandwiches.
